MAP HOLDER

Victor Percy Drury, York County, Ontario,
Canada

Application May 31, 1949, Serial No. 96,349

6 Claims. (Cl. 40—85)

1
This invention relates to an improved road-map holder, and the objects of the invention are:

1. To design a device for use especially in motor cars by means of which one or two road maps may be housed, and readily withdrawn therefrom for study on either side.

2. To control the withdrawal and housing of one of a plurality of maps by elastic means common thereto, thus providing a very compact and relatively inexpensive article.

3. To provide means to prevent the elastic means, in action, withdrawing a map completely within the housing so that one end may be exposed and readily grasped when required.

4. To provide means to prevent the elastic means from winding a map up when it is desired to keep it out for study and thus avoid the tiresome act of physically opposing the housing action of said elastic means, and which means may be used to increase the condensation of a coil spring where the metal has lost some of its resiliency.

5. To provide means whereby a complete change of maps may be readily effected without permitting the coil spring to expand.

6. To provide means at one end of the map holder to prevent lateral displacement of the coils of the particular type of spring that may be used, said means also providing bearings for the map spindle adjacent one side of the maps to prevent any tendency of the spindles to flex.

Various other objects of the invention will be set forth in the following specification.

In its broadest conception the invention consists of a coil spring composed of two coiled sections and an intermediate section coupling the coiled sections together; two spindles mounted in parallel relationship in a suitable support, to one of which one of said coiled sections is secured, and to the other of which the other coiled section is secured and a stationary retainer spacer unit that is immovable in said housing located adjacent the inner sides of said coil sections to latterly maintain the same in position.

The invention further consists in condensing a spring section by manually rotating the spindle therefor after the map thereon has been removed therefrom; means to bolt said spindle against rotation while the map is being attached thereto, and means to prevent the complete withdrawal of the map by its spring-driven spindle into the map casing so as to maintain the condensed spring section in its condensed state, said means preferably permitting the ready grasping of the map when it is desired to withdraw it.

2
The invention specifically further consists of a spring-controlled pin movably mounted in the outer end of each of the map spindles at one end of said support whereby either pin may be, at will, brought into contact with said support to prevent the rotation of the map spindle carrying same, and whereby both the said map spindles may be individually rotated by hand to condense said coil spring after maps have been removed therefrom, as hereinafter more particularly explained.

Fig. 1 is a side elevation of the device.

Fig. 2 is a longitudinal section centrally of the device.

15 Fig. 3 is a vertical section on the line 3—3, Fig. 2, showing a coil spring in end elevation.

Fig. 4 is an end view of one end of the device showing the means to prevent the rotation of either spindle to increase the condensation of a spring.

10 Fig. 5 is a vertical section of the line 5—5, Fig. 2.

Fig. 6 is an end elevation of a coil spring showing a modified form of the spring shown in Fig. 3.

Fig. 7 is a side view of a spring in the form of a spiral spring.

Fig. 8 is a side elevation of Fig. 7.

Fig. 9 is an end elevation of another modified form of coil spring, and

Fig. 10 is a cross section on the line 10—10, Fig. 1.

In the drawings, like characters of reference refer to the same parts.

35 The chief novel feature of this invention resides in the type of spring used. In the coiled and spiral types, the forms preferably used, each section of a spring depends upon the other to function, and at times, each section draws from the other. The manner in which the ends of the sections are secured to the spindles determines the positions of the slots in the casing enclosing the springs and their spindles, and the direction of condensation and expansion of the sections of the spring, and hence the direction of rotation of their spindles.

40 The form of spring shown in Fig. 3 requires that the slots in the casing for the maps be located one near the top of the casing and the other at the bottom thereof. The intermediate section of the spring coupling the two coiled sections together lies more or less tangential to the convolutions. Here the spindles rotate in opposite directions and the map on the upper spindle feeds over the upper side thereof, and

55 55

the map on the lower spindle feeds under the lower side thereof. This is also true of the forms of spring shown in Figs. 7, 8 and 9.

By locating the intermediate section of a spring diagonally between the two coiled sections thereof, as in Fig. 6, each part of the spring condenses and expands in the same direction; hence the slots in the casing can be located closer together. Here the spindles rotate in the same direction, and the maps feed over the upper sides of the spindles.

Obviously each part of a spring may be made of material of the same length, or one part may be made of a longer length of the material, when, for example, a larger map is carried by its spindle than is carried by the spindle of its other part (Fig. 2).

The coil springs are made of suitable material such as ribbon steel (Figs. 3 and 6) and the spiral springs (Figs. 7 and 9) are made of steel wire.

The support for the spindles 2, is preferably in the form of a tube 3, of any suitable shape, the ends of which are closed by the caps 4, in which the said spindles are journalled. In Figs. 2, 3, 6, 7, 8 and 9, each spring consists of two sections 7 and 8 connected together by an intermediate section 9.

In the disclosures made, the ends 5 of the springs are secured to their respective spindles in any suitable way. Where a spring is made of steel ribbon, one end of each spindle 2, is longitudinally slotted to receive the ends 5 as shown at 6, Fig. 2.

By any suitable means, such as the tape 10, secured at each end to a spindle 2, and operating through a slot 12, a map 11, is wound around each of said spindles. In Fig. 2 a map is shown as withdrawn from the casing 3, and of course the section 8 of the spring is condensed. If a map on either spindle should be longer than the map on the other, the section of the spring mounted on the spindle carrying the longer map can draw from the other section of the spring.

To keep the coils of a coiled spring (Fig. 2) from lateral displacement, a spacer 13, is used. This spacer is slotted as at 14, to receive the reduced ends of the spindles 2, and will butt against the unreduced ends of said spindles when placed within said casing.

A pin 15, is movably mounted in the ends of each spindle 2, extended beyond one end of the casing 3. Between the head 16, of each pin and the spindle is a spring 17, the function of which is to keep the enlarged end 18, of each pin in contact with its spindle (Fig. 4) and so permit the free rotation of this spindle by the post a, carried by the cap 4.

By moving one of the pins 15 to move its enlarged end into contact with the post a, this post will prevent the rotation of the spindle 2, carrying this pin and hence a map may be retained in the position shown in Fig. 2 and be thus examined at leisure.

To condense either section of a spring of the character described, the map mounted on the spindle dominated by the weaker section is uncoupled from the tape 10, by withdrawing the rod 19, from the map and the tape, the tape is pulled into the casing 3, and wound around its spindle. By means of the pin 15, the spindle is turned carrying the weaker section of the spring until this latter is condensed to the desired degree. Then the end 18 of the pin so manipulated is brought into contact with the post a, to prevent

the rotation of the spindle. The tape is then pulled out of its slot and coupled to its map. By removing the end 18 out of contact with the post a, the condensed section of the spring will re-wind the map on its spindle.

To prevent the outer end of a map from being drawn into the casing, any suitable means may be employed. The preferred means is a button b, mounted thereon as shown in Fig. 10. This button is used as a finger grip to withdraw the map.

In the disclosures shown of the spring, the two sections of the spring are in alignment, though it will be conceived that in the form shown in Figs. 7 and 8, where the spring is made of steel wire, the sections need not necessarily be in alignment. In other words, each section may be on opposite sides of the intermediate, section 9.

It is self-evident that only one map spindle may be mounted in a suitable casing, and carried at the inner end thereof may be one section of a coil spring, and the other section of the spring may be mounted on a shorter spindle journalled in said casing, and means provided to control the rotation of the map spindle and condense the spring. The statement just made is clearly illustrated, in its conception, in Fig. 2.

To guide the edges of a map and thus keep them from contacting the ends of a slot it is preferred to mount on the ends of the spindles collars c, preferably made of rubber.

In Fig. 9, a modified form of the spring shown in Fig. 8, is shown. Here the coils of one section are positioned between the coils of the other section when the sections are in expanded form. The spindles are located eccentrically of the axes of these spring sections.

In this specification and the claims thereof the term "coil" is used as a generic term to embrace variously convolved forms of springs.

It must be understood that the disclosures herein are broad and comprehensive and that various changes may be made therein without departing from the spirit of the invention and the scope of the claims.

I claim:

1. In combination a coil spring composed of two coiled sections and an intermediate section coupling said coiled sections together; two spindles in parallel relationship, one at least being rotatable both spindles functioning independently of the other; a suitable housing for said spindles and spring, one of said sections being coupled to one of said spindles, and the other coiled section being coupled to the other spindle a map wound around the rotatable spindle, and a stationary retainer spacer unit in said housing located adjacent the inner sides of said coil sections and immediately between one of said coil sections and said map.

2. A map holder comprising two parallel spindles both functioning independently of the other; a map wound around each of said spindles; a coil spring composed of two coiled sections which are coupled together by an intermediate section thereof tangential to the convolutions, one coiled section mounted on and secured to one end of one of said spindles, and the other mounted on and secured to the adjacent end of the other spindle, means to house and carry said spindles and said spring and a stationary retainer spacer unit in said housing located immediately between each coil section and the ends of the maps on said spindles.

3. In combination a longitudinally-slotted cas-

ing; two spindles longitudinally mounted therein; a coil spring composed of two coupled coiled sections, one section being coupled to one of said spindles, and the other coiled section coupled to the other spindle; a map for each of said spindles; detachable means whereby said maps are coupled to said spindles; means by which the desired spindle, after its map has been detached therefrom, may be rotated to condense the spring when necessary, a post, said last means being selectively movable to engage the post to prevent the rotation of the spindle by the spring, and means carried by the front end of the removed map adapted to contact said casing when the map is coupled to and re-wound on its spindle through its slot in said casing when its spindle has been allowed to rotate.

4. In combination a housing; a coil-spring provided spindle longitudinally journaled in said housing and projecting beyond one end thereof; a spring-provided pin transversely mounted in said projecting end, and a post carried by said housing adjacent said projecting end of the spindle and adapted to be contacted by said pin when it is desired to prevent the rotation of said spindle by its spring.

5. In combination a coil spring composed of two coiled sections and an intermediate section coupling said coiled sections together; two spindles in parallel relationship, one at least being rotatable; a suitable housing for said spindles and spring, one of said sections being coupled to one of said spindles and the other coiled section being coupled to the other spindle; a map wound around one of said spindles; means for detachably coupling said map to its spindle which latter projects beyond said housing, and a spring-provided pin carried by said projecting end

adapted to be manually manipulated to turn said map spindle to condense the spring section carried thereon, a post, said pin movable to engage the post to prevent the spindle from rotating while the map is coupled thereto, and means to prevent the complete withdrawal of the map into said housing when the map spindle is allowed to rotate.

6. In combination a coil spring composed of two coil sections and an intermediate section coupling said coil sections together; two spindles in parallel relationship one at least being rotatable and both functioning independently of the other; a suitable housing for said spindles and spring, one of said sections being coupled to one of said spindles, and the other coil section being coupled to the other spindle; a manually-controlled spring-provided pin movably mounted in the outer end of each of said spindles, and a post carried by and projecting beyond said housing means with which either of said spring-provided pins may be brought into engagement at will to prevent the turning of either of said spindles.
